(57) **CLAIM**

The ornamental design for the connector for a seatbelt airbag, as shown and described.

DESCRIPTION

FIG. 1 is an isometric view of an embodiment of a connector for a seatbelt airbag showing our design.

FIG. 2 is a front view thereof.

FIG. 3 is a back view thereof.

FIG. 4 is a left side elevation view thereof.

FIG. 5 is a right side elevation view thereof.

FIG. 6 is a top plan view thereof; and,

FIG. 7 is a bottom plan view thereof.

Elements identified in broken lines in the accompanying drawings form no part of the claimed invention.

1 Claim, 3 Drawing Sheets---
